EXPANSIBLE CLEANING BRUSH FOR HOT-AIR FURNACE RADIATORS OR THE LIKE

Walter N. Hadley, Chicago, Ill.

Application February 9, 1946, Serial No. 646,589

6 Claims. (Cl. 15—162)

1

This invention relates to cleaners, particularly for the radiators of hot-air furnaces or for tubes and channels which are apt to have accumulations of material therein or to become stopped up and especially where the entrance opening thereto is smaller than the inside of the tubes or channels. Because of the inconvenience of doing the work and the dirt and grime attendant upon the same, it is customary to clean such radiators but once a year, and that most often by some outside service company making a business of that kind of work. This is usually done in the summer season. But the efficiency of the furnace is greatly reduced by such occasional cleaning. The soot and fly ash accumulations cling to the surface of the radiators, through the walls of which the heat must pass if it is to do its intended work, and in thicker and thicker layers from day to day. Such material is a heat insulator and the efficiency of the radiator is greatly reduced thereby. Moreover, such deposits are greater when the furnaces are but lightly fired, as in the milder weather of fall and early winter, because the combustion of the fuel is not so complete, so that when winter comes and the full or greatest efficiency of the furnace is needed, the unclean condition of the radiators prevents such efficiency. Besides, the accumulation of such material tends to cut down the draft of the furnace, resulting in still less perfect combustion, the deposit of more material and a greater loss of efficiency and the production of useful heat.

It is an object of this invention to provide a simple tool for the convenient and effective cleaning of such radiators without attendant grime and dirt to person and clothing, so that the householder may do the work without discomfort. If the pipe, as is common, is erected with a T joint with a removable cover instead of an elbow on the cast extension smoke outlet, then the radiator may be cleaned without putting out the fire in the furnace and allowing it to cool down entirely, and therefore may be done often enough in the heating season to keep the radiators in their most efficient heat-radiating condition, thereby saving in fuel, keeping the furnace in its best condition at all times, including when it is most needed, as in the colder weather, and maintaining the proper draft conditions at all times.

In carrying out the invention, the tool is provided with an operating stem or shaft or handle of sufficient length and resiliency to be passed into and through the curved passages of the radiator to be cleaned and out at the opposite side. The stem carries suitable brushes expansibly

2

and resiliently mounted thereon whereby the same may be folded together about the stem for insertion into the radiator and then be expanded to engage the inside walls thereof to scrape and sweep their more or less rough and irregular surfaces to remove therefrom the soot and fly ash clinging thereto, and to push the same out at the opposite side where it may be caught in a pail or suitable receptacle. The stem is provided with means at its forward end to curve and steer it through the exit channel. By repeating the operation for the other side passage of the usual radiator, the radiator can be thoroughly cleaned in a few minutes. When done, the tool may be shaken free of the material and collapsed and put aside until the next time the radiator is to be cleaned.

The device is preferably made in three sections. The middle section may be used to clean the horizontal smoke pipe if it is erected with a T joint and removable cover instead of an elbow. Thus both radiator and pipe may be cleaned while the fire is low, in a few minutes. The heat above need not drop but a few degrees during the cleaning.

Other features, advantages and objects will appear from the description and claims to follow, in connection with the accompanying drawings which illustrate, by way of example but not of limitation, an embodiment of the invention, and in which—

Fig. 1 is a side view of the tool more or less in perspective omitting the extensions of the handle;

Fig. 2 is an end view of the same, looking in the direction of the arrows on the line 2—2 in Fig. 1;

Fig. 3 is a diagrammatic view at reduced scale of the complete tool with handle extensions;

Fig. 4 is a perspective view of the first extension of the handle;

Fig. 5 is a similar view of the second and end extension of the handle;

Fig. 6 is a cross-section on the line 6—6 of Fig. 1 of the detachable connection between extensions;

Fig. 7 shows in diagram the tool being used in cleaning the radiator of a furnace;

Fig. 8 is a perspective detail of the stem coupling; and

Fig. 9 is a perspective detail of the bottom brush frame.

As shown, a stem, shaft or handle 10, which may be of twisted spring wire, giving it stiffness and some resiliency and flexibility, is provided with a plurality of brush-carrying radiating arms or ribs 11 which may also be of spring wire, single strand, or otherwise, connected at their forward

inner ends to the stem 10 in such manner as to permit them to be swung and expanded outwardly from the stem or to be collapsed, drawn or folded inwardly relatively close to and about the stem. This connection may be a small twisted wire or other ring 12 surrounding the stem 10 and suitably connected thereto, as by threading the wires thereof or other wires diametrically across the ring and through, between or around the strands of the stem as indicated at 13, or in any desired manner. The ends of ribs 11 may be looped around this ring 12, at suitably spaced intervals, or connected therewith in any desired manner so as to pivot or hinge thereon in their expanding and collapsing movements and maintain their spaced relation on the ring. The outer ends of these ribs are bent laterally at appropriate angles and carry suitable brushes 14 to sweep the inside surfaces at the top and sides of the radiator passage to be cleaned.

The passages through the radiators of furnaces are usually not exactly circular in cross-section except possibly at the entrance and exit, but may be somewhat elliptical, with the longer axis vertical or with substantially straight vertical sides and rounded ends. Moreover, the surfaces are apt to be more or less uneven. The brushes 14, when expanded and in use, are intended substantially to overlap circumferentially and reach and sweep all such surfaces in a single forward pass of the device therethrough, though, if desired, it may be pushed and pulled back and forth. The resiliency of the ribs and of the structure as a whole enables this to be done, that is, the brushes to reach all surfaces. Since the brushes thus cover the entire periphery of the sides and top of the passage when viewed in cross-section, any interference endwise, one with another, when they are collapsed or folded up or in working positions, is guarded against by making some of the ribs 11 slightly longer and some shorter as indicated in Fig. 1, or otherwise. This permits the brushes to reach and cover the inside surface of the passage and to pass and overlap each other when so collapsed.

These arms or ribs 11 are operated by stays, braces or rods 15 preferably of relatively heavy single-strand stiff spring wire like the ribs 11, having their outer ends hooked or looped into other loops 16 formed in or attached to the ribs 11 and their inner ends looped around or otherwise attached to a small twisted wire or other ring 17 surrounding and movable along the stem 10. This ring 17 is manually moved along the stem 10 when desired, as by a twisted wire or other rod 18 which is rigidly enough connected thereto to push and pull the same along the stem to expand and contract the brushes and to hold them in their expanded working positions while maintaining the substantial perpendicularity of the plane of the ring to the stem. In fact, as indicated, the ring 17 may be the prolonged end of rod 18 bent laterally to form the ring around the stem 10, the ends of the wires being suitably interlaced with the rod and ring to form a complete ring at the end of the rod.

The brushing along the bottom surface of the radiator passage is preferably accomplished by the horizontal or bottom brush 19 which is carried between wire end bracing frames 20 formed preferably of a single piece of wire bent, as indicated in Fig. 9, to form these end frames which are connected together at the top by the

member 21 which is pivotally attached in any desired manner to the stem 10. The lower rear corners of these end frames 20 and the ends of brush 19 extending between them are connected by stays 25 with ring 17, so as to be swung into working position and withdrawn therefrom, the same as the ribs 11 and brushes 14.

The material brushed from the top and sides of the passage falls to the bottom and the bottom brush 19 is therefore preferably slightly in the rear of the brushes 14. It not only serves to clean the bottom surface but to push this added material along ahead of it to the exit. Besides, the layer of material is apt to be thicker at the bottom than along the sides and top, and if, as sometimes occurs, scale forms, it is most likely to be at the bottom. This frame, consisting of the members 20 and 21, also centers or tends to center the cleaner in its travel through the radiator passage and carries the weight and downward thrust thereof in excess of that carried by the adjacent side brushes.

Opposed guiding or steering members 26 project horizontally on either side of stem 10 in advance of the ring 12 to which the ribs 11 of the brushes are connected and may be formed by loops in the wires of the stem or be otherwise formed and attached to the stem. The action of these loops in approaching the exit of the radiator passage will be described presently.

The forward end of the stem 10 preferably terminates in a bulb-like cluster of crossed loops 27, three in this instance, which also may be formed of the stem wires and together make a rounded enlarged forward end of the stem for guiding and pulling purposes as hereinafter explained.

The complete handle or stem of the device, which may be several feet in length, is preferably made sectional for convenience in handling, storage, shipping, etc. These sections, which may be designated, respectively, as A, B, and C, Fig. 3, must be connected by couplings which are dependable in use, are readily connected and disconnected, which make the sections act as one flexible member in the use of the device (see Fig. 7) and be inexpensive.

In order to accomplish this, preferably, the meeting ends of the sections of the stem wires are bent back and forth into a half or partial helical coil formed as indicated at 30 and 31 in Fig. 8, the main difference between the two being that in the lower or outer coil 30, one or more of the strands extend like chords across the circle as at 32, instead of following around the ring. The two coils are coupled by pressing the upper semi-coil 31 down into the lower coil 30, the locking bars 32 passing up between adjacent coils in the coil 31 and the wires of the two coils snugly nesting together as indicated in Figs. 1 and 6, so as to form a strong, axially rigid, inextensible and yet laterally resilient coupling between the sections of the stem. To insure against any possibility of the undesired lateral separation of these two half coils, a locking pin 36, which may be an elongated wire loop secured to a ring 37, preferably of the same material and integral therewith and which is slideable on the stem 10, is slid into the nested coils and under the locking strands 32. This effectively prevents the possibility of the nested coils separating or getting out of place with respect to each other.

The sections A and B as well as sections B and C of the handle stem are thus readily con-

nected for use and as readily disconnected for other purposes. Other forms of couplings may be used but that shown is preferred.

The end of rod 18 for expanding and folding up the brushes is provided with a few turns of partial coils 40 like the longer coils 30 and 31, which when the arms or ribs carrying the brushes are expanded sufficiently may be similarly pressed laterally into the nested coils 30 and 31 forming the coupling of sections A and B of the stem, and thereby hold said ribs and the brushes in their adjusted expanded position until it is desired to release and fold them together. As stated, the material is spring wire, and the three can be thus compressed together in the same way as the two, the wires springing enough to permit the same and the key 36 locking all three together. The short coil 40 may be placed in different positions along the longer coils 30 and 31 to provide for suitable adjustment of the extent of the working expansion of the brushes.

Fig. 7 represents in diagrammatic plan the passages needing cleaning in a typical furnace, the gases coming up from the center 50, dividing and passing around the passages 51 and thence out the exit passage 52, the passage 53, which may be termed the entrance passage, being normally closed by a suitable removable cap.

Now to clean the radiator, the cap at the entrance 53 is removed and the front end of the folded tool inserted. While here the entering end of the tool must go into one of the side passages 51, it is fairly easy so to direct it in order to get the tool to take the desired channel, say the one to the right. Once the bulb 27 is on its way, the cleaner can be pushed along thereafter. When the smaller entrance is passed by the folded cleaner, the brushes are expanded by pushing the rod 18 forward and snapping its end 40 into the coupling 30-31 and securing it there. Although passage 51 may not be exactly circular in cross-section, the spring ribs 11, the arms 15 and the brushes themselves will conform to the variations and the brushes will suitably engage the entire inside surface to sweep and scrape the same and push the swept material along as the stem of the cleaner is pushed further into the passage.

The brushes, it may be said, are of any suitable type for the work in hand, though commercial fiber bristle brushes with sheet steel or metal backing, which may be bent or folded around the laterally bent ends of the ribs 11 and secured thereto, are contemplated. As indicated, however, the bristles need not extend entirely around the wire ends, as on the inside of the circle formed by them.

As the stem of the cleaner is fed forward, the bulb 27, loops 26 and the bottom brush 19 and its frame 20-21 will center and keep the brushes substantially centered in the curved passage 51 in order thoroughly to brush, sweep and scrape the soot, fly ash and scale material from the inside walls and push it along toward the exit.

When the stem comes to the first coupling or immediately thereafter on its way into the passage, there is preferably a semi-circular guiding and scraping plate brush 60, Fig. 4, located on the section B of the stem 10 immediately in the rear of coupling member 31. This blade, though standing normally transverse to the stem, may be unable to pass the entrance to the radiator in that position. Accordingly, the stem has a lateral bend 61 in back of the blade and the opening for the stem through the blade is sufficiently large to permit the blade to be swung around on

this bend 61 so as to lie longitudinally of or parallel to the stem, as indicated in dotted lines in Fig. 3, during its passage into the radiator. The stays or braces 62, also loosely or hingedly connected with the blade 60 adjacent its ends and detachably hooked at their other ends into the stem 10, as by suitable apertures therethrough between the wires or loop eyes provided therefor, and which normally hold the blade transverse to the stem, are disconnected from the stem for the swinging of the blade longitudinally thereof and are again connected before the stem and blade get too far into the passage, so that the blade may then again be positioned transversely of the stem and be held in that position by the stays and the bend 61 during the remainder of its passage through the radiator channel.

This blade 60 has its lower edge curved substantially like the channel lower surfaces and is preferably provided with a suitable brush therealong. This plate and brush not only guide the stem and center it in the channel, but scrape off any material, such as scale or the like, still adhering to the surface and gather up any material escaping the brushes 14 and 19.

As the cleaner is pushed toward the exit 52 of the radiator channel, the resilient stem is crowding the guide loop 26 over to the outside so that it engages the corner at the outlet 52 and flexes the stem and diverts the bulb 27 into the exit channel 52 which, on being further pushed, guides the stem and brushes thereinto. The brush may thus be pushed clear through and out the exit, or as soon as the bulb emerges from the exit it may be grasped and the entire cleaner pulled out the exit. Although the brushes are still expanded at this time, the resilience of their mountings and of the cleaner as a whole enables them to be pulled through without disengagement of the rod 18 and coil 40. The same is true of the last brush 60. It may likewise be pulled out and around the bends without being swung longitudinally of the stem. If there is not enough room between the furnace 50 and the adjacent wall of the building or other obstacle to enable the entire device to be so drawn out, the sections may be disconnected as they emerge. It is contemplated to make the expansion section, that is, section A, as short as its mechanism allows. The swept material is also drawn out the exit 52 and may be caught in a pail or receptacle and disposed of.

This cleaning operation may then be repeated for the other half of the radiator channel 51, so that when done, the channels are swept clean of the soot, ash, etc., and are in their most efficient condition for heat transmission.

While the brush has been described for cleaning passages more or less circular in cross-section, it may be used for other purposes, such for instance as cleaning a chimney having a rectangular or square section, though in such instances some of the ribs may be longer and some shorter than here shown, so that in expanding the brushes assume more the contour of the passage. For the cleaning of vertical passages, too, the brush 19 may not be required. The second section is usable separately for cleaning pipe. If there is an upright and a horizontal pipe and a T-joint connecting the two instead of an elbow, this section may be advantageously used for cleaning the horizontal pipe. In the case of a furnace of the type depicted, if spots on the surfaces are left untouched at the entrance

and exit they may be readily brushed separately by the second section.

From the foregoing it is apparent that a light and convenient cleaning tool for the household has been provided which is most effective in cleaning radiators or other passages, that is simple in construction and operation, is of low cost, and may be used by anyone, even the housewife without the usual accompaniment of dirt and grime. Moreover, such cleaning may be done while the furnace is still going, and since it is done in the direction of the draft in the furnace, the dust is carried along with it and does not issue into the room or the face of the operator. The cleaning is done by a single push stroke of the device through each side of the "doughnut" radiator, as it is sometimes called, and all passages, including the chimney, may be cleaned in a few minutes from the basement or wherever the furnace is located and without appreciably cooling the furnace or lowering the temperature of the rooms above. While but one embodiment has been shown, it is apparent that various changes may be made therein without departing from the principle or scope thereof as set forth or intended to be set forth in the following claims.

I claim:

1. A tool for cleaning the inside surfaces of the tortuous passages of hot-air heating furnace radiators or the like comprising a central operating stem or handle having lateral flexibility and resiliency and longitudinal rigidity enabling it to be pushed through the curved passage of the radiator from the outside, a cluster of brushes surrounding the flexible handle, spring ribs carrying said brushes at their outer ends and secured in pivotal relation at their inner ends to the handle, spring stays connecting said ribs intermediate their ends with the handle, a movable rod alongside the handle with which the inner ends of said stays are connected, and manually operated means associated with the handle for moving said rod therewith either to fold the ribs and brushes compactly toward and about the handle or to expand and hold them in working position, whereby the cleaner may be folded into compact form when not in use or for insertion through a restricted entrance into the passage to be cleaned and thereafter expanded into working positions to clean the inside of the passage as the cleaner is pushed therethrough by the handle from the outside, said stem having a forward end projecting forwardly beyond the brushes and having guide means thereon adapted to steer the brushes into the proper channel, the whole constituting a resilient flexible brush and stem or handle enabling it to adapt itself to the form and curves of the passage and to clean the same by a single push-stroke therethrough.

2. A tool for cleaning the inside surfaces of the tortuous channels or passages of hot-air heating furnace radiators or the like comprising a central operating stem or handle having lateral resiliency and flexibility and longitudinal rigidity enabling it to be pushed through the radiator from the outside, a cluster of brushes resiliently mounted on said stem in foldable relation for compactness and insertion through a restricted entrance and expandable into working position inside the radiator, said brushes when expanded engaging substantially the entire inside surface of the channel surrounding them, and manually operated means associated with the stem

for so folding said brushes and for expanding them after entrance into the radiator, the bottom brush of the cluster being spaced a distance to the rear of the others to catch and sweep forward the material falling from said other brushes and being connected to the said stem to tend to center the same and the brush as a whole in the channel when the brush is being pushed therethrough.

3. A tool for cleaning the inside surfaces of the tortuous channels or passages of hot-air heating furnace radiators or the like comprising a central operating stem or handle having lateral resiliency and flexibility and longitudinal rigidity enabling it to be pushed through the radiator from the outside, a cluster of brushes resiliently mounted on said rod in foldable relation for compactness and insertion through a restricted entrance and expandable into working position inside the radiator, said brushes when expanded engaging substantially the entire inside surface of the channel surrounding them, and manually operated means associated with the rod for so folding said brushes and for expanding them after entrance into the radiator, and a braced frame for supporting each end of the bottom brush of the cluster, said bottom brush being spaced from and positioned in the rear of the other brushes of the cluster.

30 4. A tool for cleaning the tortuous passages of the radiator of hot-air heating furnaces or the like by a single push-stroke therethrough comprising a central operating stem or handle and a brush carried thereby, said stem or handle having lateral flexibility and resiliency and longitudinal stiffness to enable it and the brush carried thereby to be pushed into, through and out the tortuous passage, the said brush including a cluster of brush segments resiliently mounted on said stem in foldable relation for compactness and insertion through a restricted entrance to the passage and expandable into working position inside the passage, said brush segments when expanded engaging substantially the entire inside surface of the passage, a rod manually operated and associated with the handle for so folding said brush segments and for expanding them and holding them in expanded position after entrance into the passage, and laterally extending guiding loops on the stem in advance of the brush but spaced from the end of the stem to assist in steering and centralizing the same about curves in the passage and to flex the end of the stem angularly into a side channel of the curved passage such as the exit of the radiator.

5. A tool for cleaning the tortuous passages of the radiator of hot-air heating furnaces or the like by a single push-stroke therethrough comprising a central operating stem or handle and a brush carried thereby, said stem or handle having lateral flexibility and resiliency and longitudinal stiffness to enable it and the brush carried thereby to be pushed into, through and out the tortuous passage, the said brush including a cluster of brush segments resiliently mounted on said stem in foldable relation for compactness and insertion through a restricted entrance to the passage and expandable into working position inside the passage, said brush segments when expanded engaging substantially the entire inside surface of the passage, manually operated means associated with the handle for so folding said brush segments and for expanding them expanded after entrance into

the passage, said flexible stem projecting beyond and in front of the brush, and lateral extensions on said projection spaced from the free end thereof adapted to engage the side wall of the channel adjacent the outlet to flex the end of the stem into said outlet as the brush is pushed through the channel.

6. An inside cleaner for relatively long tortuous channels comprising a relatively long twisted wire stem or handle, a brush adjacent one end of the handle for cleaning the inside surface of the channel through which it is pushed from the outside, said brush being foldable and expansible, and means including a twisted wire rod substantially paralleling the handle manually movable longitudinally to fold or expand the brush, said handle being in detachable sections, the wires of the sections being bent at the ends into a closely related continuous series of short zig zag transverse portions, said series on each section being transversely curved into arcuate form and the series on adjacent ends of the sections being adapted to be nested together laterally, with the wires thereof engaging each other longitudinally of the sections to form a complete flexible coupling therebetween and detachable laterally to separate the sections, the free end of said wire rod having its wires formed into a similar zigzag arcuate series adapted to nest with those of the adjacent handle coupling to hold the brush in its expanded condition. 30
